UNITED STATES PATENT OFFICE.

GEORGE HANDLEY, OF PALMERS GREEN, ENGLAND, ASSIGNOR OF ONE-HALF TO PERCY
WILLIAM BULLOCK, OF LONDON, ENGLAND.

ROTARY PUMP.

1,335,577.

Specification of Letters Patent. Patented Mar. 30, 1920.

Application filed October 24, 1919. Serial No. 333,023.

To all whom it may concern:

Be it known that I, GEORGE HANDLEY, a subject of the King of Great Britain, residing at Palmers Green, in the county of Middlesex, England, have invented new and useful Improvements in Rotary Pumps, of which the following is a specification.

This invention relates to the eccentric displacement type of air pump or compressor in which a cylindrical rotor is mounted eccentrically within a cylindrical chamber of larger diameter, and is operated by an eccentric fixed upon a shaft passing through the cylindrical chamber the rotor having formed upon it or fixed thereto a radial blade, division plate, or stem moving in a slot provided in an oscillatory member. The said oscillatory member is provided with ports adapted to register with other ports in the pump casing or in a fixed bushing partially surrounding the oscillatory member, the registration being arranged to take place when the air or gaseous fluid in the pump chamber has attained a certain desired pressure, or when the rotor has completed a pre-determined portion of its cycle.

It is obvious that in any contrivance of this class in which only two elements with ports therein are employed to provide registration, namely the oscillatory member and the fixed bushing, the width of the ports is strictly limited by the circumferential movement of the oscillatory member. This is the maximum possible width, since if made wider than this, the ports would overlap and be useless. Also in actual practice the ports must be made very much narrower than this maximum width, since the pressure attained at one half stroke is little more than one atmosphere.

Now the angular movement of the oscillatory member is necessarily small and a port having a width which is much narrower than the arc traced by the radius of this member would in practice be inadequate to pass any considerable quantity of air, and the effect of trying to force the contents of the pump chamber through such a small opening would be to greatly increase the power required to drive the pump and to unduly heat the air or gaseous fluid and the pump itself.

By the present invention the above men-

tioned difficulty is overcome by providing a third element with a port therein, so that all three ports must register before the air or gaseous fluid can escape. Such third element may be constituted by the stem of the rotor or by the bushing or sleeve surrounding the oscillatory member; in the latter case the said bushing or sleeve instead of being fixed is made to oscillate through an angle greater than the angular movement of the oscillatory member in which the stem of the rotor slides.

Since in this arrangement the contents of the pump chamber are cut off for preliminary compression before reaching the opening in the stem, the compressed contents of the latter cannot expand back into the pump chamber and the amount of clearance space is reduced to a minimum.

Moreover according to the present invention, in order to dispense with the usual type of outlet valve to relieve pressure upon the pendulum stem, I provide one or other of the following contrivances, viz:—A plate or disk or segment of a plate or disk at one or both ends of the oscillatory member. Such plate or disk, or portion or segment thereof, provided with the necessary ports or openings, is given its proper motion to control the opening and closing of the outlet from the pump. For this purpose it may be operated either directly by a link or links from any moving portion of the pump or by reaction from a fixed part of the pump. The same result can be secured by providing a D-shaped channel in the stem of the rotor, the mouth of this channel being near the bob of the rotor, and the exit some distance up the stem in the face thereof, a port in the oscillatory member being provided to communicate with the channel in the stem at certain times and with an outlet in the body of the compressor. In this case the sleeve surrounding the oscillatory member is fixed. In these arrangements the passage in the rotor stem is not necessarily cut off from the pump chamber until the cycle of the rotor is completed.

In the accompanying drawings,

Figure 1 is a half end elevation with the end cover plate removed, and half transverse section of a pump or compressor constructed according to my invention.

Fig. 2 is an end view of a portion of a compressor with cover plate and gland removed, illustrating a modification.

Fig. 3 is a section taken on the line 3—3 5 of Fig. 2.

Figs. 4 and 5 are views of two details hereinafter described.

Fig. 6 is an end view of the oscillatory member.

10 Fig. 7 is a side view of a portion of the oscillatory member.

Figs. 8 and 9 are partial transverse sections and partial end elevations with the cover plate removed of a further modification, showing the moving parts of the pump 15 in two different positions.

Fig. 10 is an end elevation with the end plate removed illustrating a further modification.

20 Fig. 11 is an end view of the rotor and stem.

Fig. 12 is a section on the line 12—12 of Fig. 11, and

25 Fig. 13 is a side view of a cylinder or plunger type of rotary valve which is mounted in the stem of the rotor.

Fig. 14 illustrates partly in section a further modification in which the outlet is at the side, and the stem of the rotor has a 30 D-shaped channel, the sleeve being stationary.

Like letters represent corresponding parts in the several figures.

Referring to Fig. 1, A is the compressor 35 body; B the rotor mounted on an eccentric C carried by the shaft D; E the stem of the rotor; F an oscillatory member slotted at F' to receive the stem E, and perforated at F² to form the outlet for the compressed 40 fluid. G is a fixed sleeve in which the member F oscillates; H is the inlet in the pump body, and J the outlet. The sleeve G is slotted at G' opposite the inlet H, also at G² opposite the outlet J, and is further 45 formed with a channel at G³ leading to a port G⁴.

The stem E of the rotor is furnished with an outlet channel or port E' the entrance to which does not at any time open directly 50 into the pump chamber but always remains within the oscillatory member F. Said oscillatory member is furnished with a port or channel F⁸ adapted to register at certain times with the port G⁴ in the sleeve G, and 55 with the port E' in the stem E. The construction of these ports is such that the passage in the oscillatory member discharges through the opening in the upper part of 60 the oscillatory member to the pump outlet. But the port in the stem does not register with the inner end of the passage in the oscillatory member until the required portion of the cycle of the rotor has been completed.

It will be seen that before there is an outlet for the compressed fluid it is necessary for there to be registration between the ports G⁴ and F⁸, and also between the ports F⁸ and E'. This feature constitutes the 70 novelty of the arrangements so far described, and secures the advantages above specified.

Referring to Figs. 2 to 7, K is a disk mounted eccentrically in an adjusting ring 75 L and provided with a port M which registers with an outlet N in the cover plate O, the whole constituting a mechanically operated disk valve. The disk K is oscillated by a pin P working in the slot K' in the 80 disk K, said pin P being fixed in the end of the oscillatory member F and carrying an antifriction roller P'. The member F and disk K turn about different axes, and the relative positions of these axes can be 85 changed by adjusting the ring L which carries the disk K. This adjustment is effected by means of a screw R the threads of which engage with teeth on the periphery of the ring L. In this way the ports M and N can 90 be made to register at different points in the cycle of the rotor B. The outlet from the oscillatory member F is shown at F².

This arrangement is suitable for side outlet e. g. when using pumps arranged in 95 series.

Referring now to Figs. 8 and 9, in this case the moving disk K indicated by broken lines is mounted and actuated as in Figs. 2 and 3 but it is not furnished with a port, 100 and is used as a means of transmitting motion to a sleeve S which surrounds the oscillatory member F. For this purpose the sleeve S is furnished with a pin S' and roller S² working in the slot K' of the 105 disk K.

The moving sleeve S works in a fixed sleeve G and is provided with inlet and outlet ports S⁸, S⁴ respectively adapted to register with the corresponding ports G⁴, G² of 110 the fixed sleeve G. Said ports S⁸, S⁴ also register at a predetermined time with the inlet and outlet passages F⁸, F² respectively of the oscillatory member F.

It will be seen that in this arrangement 115 the stem of the pendulum is relieved from all pressure, both from the pump chamber and the receiver, during the greater portion of the stroke.

Referring to Figs. 10 to 13, in this modification the stem of the rotor is bored at T to receive a cylindrical valve W the body of which is cut away to form a gap at W' so that in one position of the valve a communication is provided through the stem of 125 the rotor, which communication can be closed by turning the valve about its axis. The valve is furnished at one end with a crank pin W² carrying an antifriction roller W³ and engaging with a radial slot 130

Y' in a disk Y mounted in the end plate of the pump. Said disk Y can be turned by means of a screw Y² in the same manner as the disk K in Fig. 2 is rotated. In this way 5 the position of the slot Y' can be adjusted as required.

It will be readily understood that the oscillatory movement of the stem of the rotor produces a corresponding rotary 10 movement of the valve W and thereby opens and closes the outlet through the stem of the rotor at the required times.

The arrangement shown in Fig. 14 differs from that shown in Fig. 1 in that the outlet 15 channel E' in the stem of the rotor is D-shaped and both ends of the channel are in the face of the stem, the lower opening being near the bob of the rotor. The inner end of the outlet channel or port F² in the oscillatory member in this case is so arranged as 20 to be closed by the face of the stem E until by the movement of the stem F the exit opening from the channel E' registers with the said port F². Before there is an outlet 25 for the compressed air or gases there must be registration between the channels or ports E' and F², and also between the channels or ports F² and G².

The space above the stem of the rotor may 30 communicate with an oil chamber and be used for lubrication purposes, or it may communicate with the atmosphere and be used for cooling purposes.

The sleeve G is shown slotted at G⁵ to give 35 additional elasticity, and to enable wear between the working faces to be taken up by any suitable means *e. g.*, by the screw Z. Moreover the corners F⁵ of the oscillatory member may be grooved out as shown for 40 the same purpose.

What I claim is:—

1. In a rotary pump or compressor of the pendulum rotary type for pumping or com-

pressing gaseous fluids, the provision of three elements each having a port or passage 45 therein, said passages being so arranged that the communication between the passage in the first element is cut off from that in the second element at some part of their relative movements, and communication between the passage in the second element is 50 cut off from that in the third element at some part of their relative movements and further all three of the ports or passages are required to be brought into registration before the fluid can escape from the 55 pump.

2. A rotary pump or compressor comprising a pump body, a rotor having a stem with an outlet passage therein, an oscillatory member in which the stem slides also provided with an outlet passage, and a sleeve partially surrounding the oscillatory member and also provided with an outlet 60 passage, means for oscillating said sleeve 65 and causing it to have a greater movement than that of the oscillatory member, in which the stem slides, all three outlet passages requiring to register before the fluid can escape from the pump. 70

3. A rotary pump or compressor comprising a pump body, a rotor having a stem with an outlet passage therein, an oscillatory member in which the stem slides, also provided with an outlet passage, said two passages only registering when the rotor has completed a predetermined portion of its cycle, and a sleeve partially surrounding the oscillatory member and also provided with an outlet passage, all three of which outlet 80 passages are required to register before the fluid can escape from the pump. 75
